H. J. ROUND ET AL

WIRELESS SIGNALING SYSTEM

Original Filed March 30, 1921

Inventor
HENRY J. ROUND
AND A. MCLELLAN

By their Attorney

Dr. J. Adams

UNITED STATES PATENT OFFICE.

HENRY J. ROUND, OF LONDON, AND ARCHIBALD McLELLAN, OF SWANSEA, ENGLAND,
ASSIGNORS TO RADIO CORPORATION OF AMERICA, A CORPORATION OF DELAWARE.

WIRELESS SIGNALING SYSTEM.

Original application filed March 30, 1921, Serial No. 457,152, and in Great Britain April 8, 1920. Patent No. 1,517,654, dated December 2, 1924. Divided and this application filed April 23, 1924. Serial No. 708,362.

This application is a division of our Patent No. 1,517,654, of December 2, 1924, for wireless signaling systems.

When a valve system consisting of a valve or valves and an oscillating circuit, is oscillating various accidental circumstances may prevent the aerial from oscillating, or may produce a variation in wave length which will be harmful to the valve or valves or to the reception of signals. It is an object of this invention to obviate the possibility of such harm.

It is a further object of this invention to provide a means for maintaining the aerial system in oscillation at a constant frequency.

The manner of carrying out the objects of this invention will be apparent from the following description taken in connection with the drawing in which:

20 The figure is a diagrammatic view illustrating the invention.

Included in the antenna circuit is a variometer L which is designed to increase or decrease the inductance of the antenna circuit in the usual manner. The oscillating circuits F and E are coupled to the aerial circuit, these circuits being tuned to a frequency greater than, and less than, the frequency of the antenna circuit respectively by 25 a predetermined amount. These circuits F and E are provided with some such means as a variable condenser whereby their respective frequencies are maintained at two predetermined values. These circuits F and E are provided with the hot wire elements T' and T which are in turn connected to the movable contact C. Connected to the contact members C' and C² is the relay G. The relay G is provided with a local circuit having 30 solenoids H' and H which are mechanically joined to the armature L.

The operation of the device is as follows:

In the event that the frequencies in the antenna circuit is altered from the value at 45 which it is designed to operate, a current will flow in either of the circuits F or E as the case may be, depending upon whether the frequency of the aerial has increased or decreased to resonance with the circuits F or E. The hot wire members T' and T are 50 sensitive to this local current and will be actuated to move the contact member C into

registration with either contact C' or C² depending upon whether the current is generated in the circuit F or the circuit E, or in other words depending upon whether the frequency of the antenna circuit has been decreased or increased. Thus the relay G is actuated to energize the coil of either of the solenoids H' or H resulting in a predetermined movement of the armature of the solenoid to effect the desired movement in the elements of the variometer. It will thus be seen that a change in the frequency of the aerial circuit automatically varies the inductance of said circuit, to restore the frequency of the aerial circuit to its normal value.

It will be understood that the circuits F and E may be tuned to allow for as large 70 or as small a variation in the frequency of the antenna circuit as may be deemed to be desirable. Whatever these adjustments may be, the mode of operation of the device is the same.

Having thus described our invention we desire to secure by Letters Patent of the United States the following:

1. In wireless signaling system, the combination of an antenna, a variable tuning 80 element associated therewith the means responsive to currents energizing said antenna for maintaining the tuning thereof substantially constant by means of said element.

2. A wireless signaling system comprising 85 an aerial, a plurality of auxiliary oscillating circuits coupled to the aerial and differing slightly in tune therefrom and means controlled by the flow of currents in the said circuits for restoring the tune of the aerial 90 to normal.

3. A wireless signaling system comprising an aerial, an auxiliary oscillating circuit coupled to the aerial and tuned slightly above 95 the normal frequency thereof, an additional auxiliary oscillating circuit coupled to said aerial and tuned slightly below the normal frequency thereof and means controlled by the flow of current in said circuits for restoring the tune of the aerial to normal.

4. In a wireless signaling system, an aerial circuit, variable means to maintain the tuning of said circuit substantially constant, and means associated with said aerial cir-

cuit to govern the operation of said variable means.

5. In a wireless signaling system, an aerial circuit including a variable tuning element, 5 a plurality of oscillating control circuits coupled to said aerial circuit, each of said control circuits being tuned to a frequency differing from that of the aerial circuit by a predetermined amount, a relay associated 10 with said control circuits, means associated with the relay and responsive to each of said control circuits to operate the variable tuning element when the frequency of the aerial circuit is changed to that of any one of the 15 control circuits, whereby the frequency of the areial circuit is restored to its normal value.

6. In a wireless signaling system having an aerial circuit, means to maintain the tuning of the aerial substantaially constant comprising, a variometer, a plurality of circuits coupled to said aerial circuit each of said plurality of circuits being tuned to a frequency different from that of the aerial by 20 25 a predetermined amount, and means to actuate the variometer when the frequency of

the aerial circuit is changed to the frequency of any one of said plurality of circuits, whereby the frequency of the aerial circuit is restored to its normal value. 30

7. In a wireless signaling system having an aerial circuit, means to maintain the tuning of said aerial circuit substantially constant comprising a variometer, a control circuit having a frequency less than the frequency of the aerial circuit, a second control circuit having a frequency greater than the frequency of the aerial circuit, both said control circuits being coupled to the aerial circuit whereby a current will flow 40 in one of said control circuits when the frequency of the aerial circuit changes to the frequency of one of the control circuits, each of said circuits being provided with a hot wire element which is responsive to the flow 45 of current therein, a movable contact associated with said hot wire elements, and means under control of said movable contact to actuate the variometer.

HENRY JOSEPH ROUND.
ARCHIBALD McLELLAN.
